UNITED STATES PATENT OFFICE.

KNUT CHRISTENSON, OF BENEDICT, NORTH DAKOTA.

ROAD MACHINE.

Application filed January 4, 1921. Serial No. 434,914.

To all whom it may concern:

Be it known that I, KNUT CHRISTENSON, a citizen of the United States, and a resident of Benedict, in the county of McLean and

5 State of North Dakota, have invented certain new and useful Improvements in Road Machines, of which the following is a specification.

The present invention relates to road machines.

The object of the invention is to provide a machine of this character which is adapted to carry out road building or repairing operations, which is effective in operation to 15 loosen, distribute and pack the material constituting the roadway, which is flexible in its action and easily controlled and which is simple and durable in construction, reliable in operation and easy and inexpensive to 20 manufacture.

Other objects and advantages of the invention reside in certain novel features of construction, combination and arrangement of parts which will be hereinafter more fully 25 described and particularly pointed out in the appended claims, reference being had to the accompanying drawings forming part of this specification, and in which:

Figure 1 is a plan view of the machine 30 embodying the invention;

Figure 2 is a side elevational view thereof;

Figure 3 is a rear elevational view, parts being broken away for the sake of illustration;

35 Figure 4 is a transverse vertical sectional view on line 4—4 of Figure 2, parts being broken away and shown in section for the sake of illustration;

Figure 5 is a detail view, partly in plan 40 and partly in horizontal section of the power plant transmission;

Figure 6 is a detail view, partly in elevation and partly in section of the transmission clutch control;

45 Figure 7 is a detail view, in elevation, of the hopper and associated mechanism, parts being broken away for the sake of illustration;

Figure 8 is a detail view, partly in section 50 and partly in elevation of the worm drive for the operating means of the dump doors;

Figure 9 is a detail view, partly in side elevation and partly in section of the meeting ends of the conveyors and supports 55 thereof;

Figure 10 is a detail view, in side elevation

of the clutch control for the lateral conveyor drive;

Figure 11 is a similar view on line y—y 60 of Figure 10.

Figure 12 is a detail view of the pawl and ratchet mechanism for the winding shaft.

Referring to the drawings wherein for the sake of illustration is shown the preferred embodiment of the invention, the numeral 65 10 designates a main frame supported upon a traction drum 11 by means of depending bearings 12 cooperating with the trunnions 13 of the traction drum and upon the steering wheels 14 of the stub axle type arranged 70 at one end of the frame.

A plow or other suitable earth working element, designated at 15, is arranged at each side of the frame and between the frame and the ground. Independent controlling means is provided for each plow or earth working element and as these controlling means are identical a common description will serve for both. The beam 16 of each plow is slidably received in a yoke 17 75 which depends from the frame 10. The yoke 17 serves to limit the downward movement of the plow and to positively support the plow in its lowermost position. Levers 18 and 19 are provided and are pivotally 80 connected at one end to each other and to the extremity of the beam of the plow, as shown at 20 and operate to control the depth of cut. The end of the lever 18 remote from the pivotal connection 20 is pivotally secured, as 85 21, to the bracket 22 fixed to the main frame. The end of the lever 19 remote from the pivotal connection 20 is itself pivotally connected, as at 23, to one arm of a bell crank lever 24 fulcrumed upon a pedestal 90 25 supported upon the main frame and controlled from a hand lever 27 by means of a connecting rod 28 pivotally secured at one end to the hand lever and at the opposite end to the other arm of the bell crank lever. 100 The hand lever 27 is maintained in position by means of a manually operated pawl 29 carried by the hand lever and a segmental rack 30 carried by the frame and adapted to cooperate with the pawl. It is obvious 105 that as the hand lever 27 is adjusted to the right or left (see Figure 2) the point of the plow is depressed or elevated, respectively by virtue of the action of the toggle constituted by the levers 18 and 19 and of 110 the bell crank and connecting rod which transmits the motion of the hand lever to

the toggle. A superstructure or frame 35 is arranged upon the main frame at a point above and adjacent the earth working elements. Horizontal shafts 36 are rotatably journaled in the superstructure. There is one such shaft for each earth working element so that these shafts in the present embodiment number two, there being one for each plow 15. A winding drum 37 is fixed to each shaft 36 and a cable 38 is arranged upon each winding drum, one end of each cable being connected to the winding drum and the opposite end being connected by means of a clevis 39 to the beam of the underlying plow. Hand wheels 40 are fixed to the ends of the horizontal shafts 36. It is obvious that by rotating the hand wheels 40 the clevis 39 which constitutes the point of support or fulcrum of the plow beams may be varied as the clevis may thus be raised or lowered vertically as desired. The clevis and its operating means coacts with the toggle etc. in controlling the depth of the cut in all positions except the lowermost position of the plow, at which time the yoke 17 constitutes the point of support or fulcrum of the plow beam.

A hopper 43 is supported upon the front end of the frame 10. The base of the hopper is open and is adapted to be closed by gravity dump doors 44 pivoted to the hopper and adapted to be closed by righting up chains 45 secured to the dump doors and entrained over the pulleys 46 to winding drums 47 upon the winding shaft 48. The winding drums 47 are connected to the winding shaft 48 by means of ratchet clutches shown in detail in Figure 12 and comprising a pawl 49 pivoted to the winding drum and a ratchet 50 fixed to the winding shaft and cooperating with the pawl 49. This ratchet clutch which is releasable at will permits of the dump of the doors without the operation of the motor or actuating means, as will hereinafter more fully appear.

Means is provided for conveying the material loosened or excavated by the earth working elements to the hopper and includes lateral conveyors designated at 55 and 56, and extending from each earth working element 15 to above the lower end of a main elevator conveyor 57 which receives the material from the lateral conveyors 55 and 56 and carries it to the hopper 43, the upper or delivery end of the main elevator conveyor extending over the upper open end of the hopper whereby the material upon the elevator conveyor falls by gravity from the delivery end thereof into the hopper. The adjacent ends of the lateral conveyor and the main elevator conveyor are supported by means of brackets 58 depending from the machine frame and braced by cross bars 59. The upper end of the elevator

conveyor is supported upon standards 60 secured at their lower ends to the hopper 43. The lateral conveyors 55 and 56 and the main conveyor 57 are all of the endless type and are all driven from a common power plant, as will be hereinafter more fully described.

A power plant is provided and serves to drive the traction drum, to drive the conveyors, and to effect the righting up of the dump doors of the hopper. This power plant preferably comprises a multiple cylinder internal combustion engine or the like designated at 65, and supported upon the main frame of the machine, as shown in Figure 5. The engine shaft 66 is adapted to be connected at will by means of a clutch 67 with a drive shaft 68, a hand lever 69 serving to control the clutch 67. A counter-shaft 70 is journaled in suitable bearings 71 adjacent and parallel to the engine shaft 60 and is driven from the engine shaft by suitable gearing which preferably comprises sprocket wheels 72 fixed upon the engine shaft and the counter-shaft, respectively and a sprocket chain 73 trained over the sprocket wheels 72.

The traction drum 11 is driven from the countershaft, preferably by means of a sprocket wheel 74 fixed to the counter shaft 70, a sprocket wheel 75 fixed to the trunnion of the traction drum and a sprocket chain 76 which runs over and engages the sprocket wheels 74 and 75. A suitable casing 77 encloses the sprocket wheel 74 and 75 and the sprocket chains 76.

The conveyor drive mechanism comprises a sprocket wheel 80 fixed to the counter-shaft and engaged by a sprocket chain 81 which runs over a sprocket wheel 82 fixed to the drive spindle 83 of the main elevator 57 to thereby drive the main elevator conveyor and also the chain 81 runs over and engages with a sprocket 84 splined to the shaft 85 mounted for rotary and longitudinal slidable motion in suitable bearings 86 carried by a superstructure frame 35. A pair of jack shafts 87 are journaled in the superstructure parallel to each other and at right angles to the shaft 85. The shaft 85 has fixed thereto oppositely disposed beveled drive pinions designated at 88 and 89 adapted for engagement with beveled driven pinions 90 and 91, respectively carried by shafts 87. It is to be noted that when the pinion 89 is engaged with the pinion 91, the pinion 88 is out of engagement with the pinion 90 and vice versa. The shaft 85 is controlled as to the engagement of its pinions 88 and 89 with the pinions 90 and 91, respectively, by means of a collar 92 fixed to the shaft 85 and having an annular groove 93 therein in which operates a fork or yoke 94 carried by one arm of a bell crank lever 95 (see Figures 130

10 and 11) pivotally supported upon the superstructure 35 and having its other arm terminating in a pin 96 operatively arranged in the slot 97 formed in the lower end of a 5 pivoted hand lever 98. The hand lever 98 is held in adjusted position by means of a manually releasable spring operated detent 99 and a cooperating rack segment 100 fixed to the superstructure 34. It is obvious that 10 by manipulating the hand lever 98 either of the shafts 87 may be selectively driven from the shaft 85. As more especially shown in Figure 3, the shafts 87 carry at their rear ends sprocket wheels 101 and 102 which are 15 fixed to the shafts 87 and which are engaged by sprocket chains 103 and 104 respectively which sprocket chains also run over and engage sprocket wheels 105 and 106, respectively, which are fixed to the spindles 107 20 and 108 of the lateral conveyors 56 and 56, respectively.

The means for driving the winding shaft 48 to effect power righting-up of the dump doors comprises a shaft 110 driven from the 25 counter shaft by means of a beveled friction pinion 111 fixed to the counter shaft and a driven friction pinion 112 splined to the shaft 110 and adapted to be engaged with the drive pinion 111 by operating the clutch control lever 113. The opposite end of the shaft 110 has fixed thereto or formed thereon a worm 114 which meshes with and drives a worm wheel 115 fixed to the winding shaft 47. A casing 116 encloses the worm gearing 30 between the shaft 110 and the winding shaft 47.

The steering control for the steering wheels comprises a hand wheel 120 secured to the upper end of the vertical shaft 121 40 which carries at its lower end a worm 122 driving a worm wheel 123, to the shaft or axis of which is fixed a crank arm 124 pivotally connected to tie rods 125 which are connected at their opposite ends to the arms 45 of the steering knuckles 127. A platform, designated at 129 is provided for the driver or operator of the machine, and when he stands on the platform he is within easy and convenient access of the hand levers and 50 hand wheels by means of which the various instrumentalities embodied in the machine are controlled.

A fuel tank for the power plant 130 is supported upon a suitable bracket 131 secured upon the main frame.

In operation only one earth working element is utilized at a time, and it is thrown into operation and adjusted as to cut by means of the hand wheel 40 and hand lever 60 27. The dump doors of the hoppers 43 are or have previously been righted-up by throwing the clutch lever 133 so that the driven pinion 112 controlled thereby is put into engagement with the driving pinion 65 111. It is to be noted that by utilizing the

friction gear destructive stresses are not set up in the motion transmission means between the transmission shaft and the dump doors, when the pinions are in operative engagement after the righting up operation 70 has been completed. When it is desired to advance the machine the hand lever 69 is thrown to engage the clutch 67 and connect the drive shaft to the engine shaft so as to impart motion to the traction drum by 75 means of the transmission shaft and sprocket gearing between said transmission shaft and said traction drum. At the same time motion is imparted to the main elevator conveyor and to the proper lateral 80 conveyor by suitably positioning of the control lever 98. During the operation of the machine the earth working element is controlled and adjusted by suitable manipulation of the hand wheel 40 and of the hand lever 27.

The earth working element 15 loosens and excavates the earth and delivers the excavated earth to the adjacent lateral conveyor which in turn carries it to the main elevator 90 from which it is discharged into the hopper, the dump doors thereof having been previously closed. The material is carried in the hopper to the desired place and may be then dumped by simply tripping the pawls 95 49 from their engagement with the ratchet teeth 50 which releases the dump doors without in any wise disturbing the motor or the motion transmission means between the motor and the winding shaft. After the 100 material constituting the road bed has been properly distributed upon the surface of the road bed and the dump doors 44 may be utilized to effect this distributing action, the earth working elements are elevated out of engagement with the road bed by means of the hand wheels 40 and the drum 11 is then utilized to properly pack the material to the road bed.

It is to be noted that in the event of the control of the earth working elements not being properly positioned or exercised, the yoke 17 automatically comes into action and positively limits the downward movement and supports the beam of the plow.

In this manner all of the various operations incident to building or resurfacing or repairing the roads and road beds may be readily and easily carried out.

I claim:

1. In a road machine of the character described, a main frame, earth working elements arranged below and at each side of said main frame, a hopper carried by the main frame, and means for conveying the material from said earth working elements to said hopper including lateral conveyors receiving the material from said earth working elements and extending inwardly toward the center of the machine, and a main 125 130

elevator conveyor receiving the material from said lateral conveyors and delivering it to the hopper.

2. In a road machine of the character described, a wheeled frame, a hopper carried by said frame, a plow arranged below and at each side of the frame, independent adjusting means for each plow, a lateral conveyor associated with each plow, each lateral conveyor being so arranged with respect to its plow as to receive the material excavated thereby, a single elevator arranged to receive the material from both of the lateral conveyors and adapted to deliver such material into the hopper, and means for driving said elevator and for selectively driving either of said lateral conveyors.
3. In a machine of the character described, a main frame, a plow arranged below and at each side of said main frame, a

hopper carried by said main frame, means for conveying the material from said plows to said hopper including a lateral conveyor for each plow arranged to receive material excavated by its plow, and a main elevator conveyor receiving the material from both of said lateral conveyors and delivering it to said hopper, a power plant, and means for driving said conveyors from said power plant including a sprocket chain directly and positively driving said main elevator conveyor, a shiftable shaft driven from said sprocket chain, oppositely arranged pinions on said shaft, jack shafts having pinions alternately engageable with the oppositely arranged pinions whereby said jack shafts are selectively driven, and sprocket gearing between said jack shafts and said lateral conveyors.

KNUT CHRISTENSON.
